Application filed March 27, 1884. Term of patent 3½ years.

To all whom it may concern:

Be it known that I, CATHERINE SHIELS, of the city, county, and State of New York, have invented and produced a new and original 5 Design for a Pattern of a Girl's Costume, (numbered 9,159;) and I do hereby declare that the engraved prints accompanying this specification convey to any one accustomed to using paper patterns a clear understanding of how a 10 garment made up by the pattern will appear.

The design shows a Princess dress that displays a fan-plaited vest upon the upper part of the center of the front, deep jacket-fronts

flaring above the waist-line and falling in deep tabs at the bottom, a sash-drapery exhibiting 15 plaits at the front and sides and a large bow at the back, coat-sleeves, and a standing collar.

What I claim as my invention, and desire to secure by Letters Patent, is—

The design for a girl's costume, as shown in 20 the engraved prints accompanying this specification.

CATHERINE SHIELS.
